ART OF LEASING WARPS

Frederick Klein, Glen Rock, N. J., assignor to
Sipp-Eastwood Corporation, Paterson, N. J., a
corporation of New Jersey

Application August 24, 1934, Serial No. 741,212

1 Claim. (Cl. 28—40)

In the preparation of a warp it is necessary to provide a lease or cross for use in the weaving and, in the operation following weaving, in uniting to such warp when exhausted a new warp, wherefore in the warping operation the warp is passed through a lease-reed between the warping machine reel and the creel or other thread-supply and pressed by the operator's arm one way (up or down) to form a shed as between certain threads—as the alternates—and the remainder and then pressed the other way to form another shed, a rod being placed in each shed as it is formed to temporarily preserve it until the rods can be replaced by lease-cords. This work is difficult to perform properly in the manner stated, to wit, without any mechanical means but the manually handled rods, and in any event it is frequently impossible of performance unless the warp is first slackened, which is undesirable because it makes possible certain disturbance of the threads.

Given a warp support, as a roller, rods extending across opposite faces of the warp for holding the warp thread portions crossed thereby in substantially side by side relation to each other, a shed-forming means, as the dents of a lease-reed and stops intervening between the dents, and suitable structure carrying the support and shed-forming means, the invention contemplates a back-and-forth-movable system including parallel cranks pivoted in said structure and a link pivotally connecting the cranks and projecting therefrom past the warp and carrying said rods.

35 In the drawing,

Fig. 1 is a side elevation of certain well known equipment used in warping and containing the invention;

Fig. 2 is a front elevation of a fragment of the cross-reed and a certain bracket thereon;

Fig. 3 is a plan;

Figs. 4 and 5 side elevations showing the lease-forming means in the positions for forming the respective sheds; and

Fig. 6 shows a detail.

Let 1 be the reel (shown only fragmentarily) of a warping machine; 2 the warping machine carriage or carrier; 3 that one (here a roller) of two supports for warp threads *a* with respect to which the warp is to undergo angular displacement to form each shed therein; 4 brackets on such carriage to receive the shed-preserving bars 5; 6 any condenser (as in my Patent No. 1,860,677) by which as usual the threads are arranged in superposed horizontal tiers; 7 the condensing

reed supported on the carriage and by which, as usual, the warp is reduced to narrow or band form before winding on the reel; and 8 a cross-reed or lease-reed supported on the carriage at 8*x* and of usual type, i. e., with stops 8*a* in some of its dent-spaces and with stops 8*b*, at a different elevation, in the same dent spaces, each series of stops constituting means, when the warp is angularly displaced, to oppose such displacement as to some of the (here the alternate) threads. The parts 6 and 7 may in some instances of warping be omitted.

Affixed to each side of reed 8 is a depending bracket 10, and in these is journaled a rock-shaft 11 having affixed thereto at each end a crank 12 and having near its mid-length a crank 13. Pivoted to each bracket is a crank 14. Each crank-pair 12—14 forms with a link 15 pivotally connecting the free ends thereof a parallel-lever system. Each link projects upwardly and the two links carry a lower rod 16 and also an upper rod 17 which is mounted in sockets in the links and removably held therein by set-screws 18. The support for the warp formed by the rods is at the approach side of the reed 7 and it tends to coact with support 3 to support the portion of the warp between them as a sheet. The normal or working position of this support is shown by Fig. 1.

If the parallel-lever system is moved to elevate 30 said support and hence the warp to the position of Fig. 4 some of the threads will be opposed by the stops 8*a* to form a shed as there shown; on depression of said system to the position of Fig. 5 those same threads will be opposed by the stops 8*b* to form a shed as there shown. The parallel-lever system here guides said support to each such position in a definite path and thereupon holds it in such position, as will be apparent. On the forming of the first shed the operator introduces therein one bar 5 to preserve the shed at the left thereof and on the forming of the second shed introduces therein the other bar 5 to preserve the shed at the right thereof, with the result that a lease or cross is formed as in Fig. 1, 45 whereupon, upon introducing permanent lease-maintaining lease-cords, the bars may be withdrawn.

The parallel-lever system is moved and upon movement here held stationary as follows: In 50 brackets 19 depending from the carriage is journaled a rock-shaft 20 having a crank 21 which is connected to crank 13 by a link 22 and also having an end crank 23 provided with a handle comprising a pin 24 slidable through the crank and 55

- a knob 24a thereon. When the handle is pushed toward the bracket its pin may enter any one of three holes 25 in the bracket to hold the system of parts including the support formed by rods 5 16—17 stationary. Said system and the link and rock-shaft 20 and its cranks form carrier means which holds this support in the definite position to which it is moved in either direction and guides it during such movement.
- 10 Having thus fully described my invention what I claim is:
- Apparatus for use in forming a cross in a warp including a warp support, rods, extending across the opposite faces of the warp, for hold-

ing the warp thread portions crossed thereby in substantially side by side relation to each other, a shed-forming means arranged between said support and rods and comprising dents 5 penetrating the warp and having in each of selected spaces between its dents spaced stops between which a corresponding warp thread extends, a back-and-forth-movable system including parallel cranks and a link pivotally connecting the cranks and carrying the rods, and means 10 to support the warp support and shed-forming means and on which said cranks are pivotally supported.

FREDERICK KLEIN.
